UNITED STATES PATENT OFFICE.

ERNEST STEAD, OF BINGHAMTON, NEW YORK.

LENS GRINDING AND POLISHING MACHINE.

1,230,530.

Specification of Letters Patent. Patented June 19, 1917.

Application filed June 1, 1915. Serial No. 31,533.

To all whom it may concern:

Be it known that I, ERNEST STEAD, a citizen of the United States of America, and resident of Binghamton, in the county of 5 Broome, in the State of New York, have invented new and useful Improvements in Lens Grinding and Polishing Machines, of which the following, taken in connection with the accompanying drawings, is a full, 10 clear, and exact description.

This invention relates to certain improvements in grinding and polishing machines adapted to be used more particularly in the manufacture of lenses for forming and 15 finishing the surfaces thereof.

The main object is to provide a simple, compact and efficient machine by which the concave or convex surfaces of cylindrical, spheric or toric lenses of one or more foci 20 and of any predetermined radius may be expeditiously and accurately ground or polished under a combined rotary and planetary action of the grinding or polishing elements.

Another object is to enable the machine to be easily and quickly adjusted for grinding the surfaces of different forms of lenses without affecting the speed ratios or direction of movement of the rotary or planetary 30 motions.

A further object is to provide simple means for slightly shifting one of the grinding or polishing elements relatively to the other to prevent the recurrence of contact at 35 any one point between the work and tool in order to reduce to a minimum the liability of producing channels or line marks in the lens.

Other objects and uses relating to specific 40 parts of the machine will be brought out in the following description.

In the drawings—

Figure 1 is a front elevation of a lens-grinding and polishing machine embodying 45 the various features of my invention.

Fig. 2 is an enlarged vertical sectional view of the same machine taken on line 2—2, Fig. 1.

Fig. 3 is an enlarged horizontal sectional 50 view taken on line 3—3, Fig. 1.

Fig. 4 is a vertical sectional view taken in the plane of line 4—4, Fig. 3.

Fig. 5 is a vertical sectional view through the gear case under the table, taken in the 55 plane of line 5—5, Fig. 2, and showing a

portion of the motor shaft and its clutch connection with the gear shaft.

Fig. 6 is a top plan of the electric switch for controlling the operation of the motor and adjacent portion of its operating mechanism.

Fig. 7 is a vertical sectional view taken on line 7—7, Fig. 6.

Fig. 8 is a diagrammatic plan of the rotary grinding or polishing tool and rotary 65 lens holder showing their relative directions of movement.

As illustrated, the machine comprises a main frame —1— adapted to rest upon the floor and having a substantially horizontal 70 bed or table —2— for supporting the various mechanism at the desired height for convenience of operation and inspection of the various mechanisms and work, the table or bed —2— being provided with a circular 75 vertical opening —3— therethrough for receiving certain portions of the driving mechanisms for the tool and work and also provided with a raised annular flange —4— surrounding the opening and concentric 80 therewith, but some distance therefrom for retaining any loose tools or work which may be temporarily supported upon the bed against accidental displacement.

Secured to the lower and upper faces of the 85 bed or table —2—, co-axial with the opening —3—, are gear case sections —5— and —6— having suitable bearings —7— and —8— centrally in their adjacent ends for receiving and supporting the adjacent portion of a 90 vertical shaft —9—, the lower end of the case section —5— and the upper end of the case section —6— being closed by caps —10— and —11—, respectively, for excluding 95 dust and other foreign matter from the working parts within the case.

The lower end of the shaft —9— is journaled in a bearing —12— in the bottom of the cap —10— and is provided with an anti-friction end thrust bearing —13—, 100 shown more clearly in Figs. 2 and 5, the intermediate portion of said shaft being connected by beveled gears —14— to a horizontal shaft section —15— which in turn is connected by a clutch or coupling —16— to 105 a co-axial armature shaft —17— of an electric motor —18—, the latter being secured in a horizontal position to the under side of the bed or table —2—.

Connected in the motor circuit is an elec- 110

tric switch —19— of any suitable construction capable of controlling the operation of the motor, and preferably of a snap-switch type having an operating member or handle 5 —20— by which the rotary part thereof may be operated.

It is preferable, however, to provide means whereby it may be operated by the foot, and for this purpose the rotary shaft 10 to which the handle is attached is provided with a ratchet wheel —21— adapted to be engaged by a pawl —22— on a co-axial rock arm —23— which is loose on the switch shaft and is connected by a link —24— to 15 one arm of a bell crank lever —25— on the under side of the bed or table —2—, as shown more clearly in Figs. 1, 6 and 7, the other arm being attached to a vertical operating rod —26— extending to a point near 20 the floor line and provided with a pedal —27—, whereby the rod may be depressed by the foot of the operator.

The rod —26— is guided in bearings —28— on one of the supporting legs of the 25 table —2— and is retracted by a coil spring —29— surrounding the upper end of the rod between the uppermost bearing —28— and a shoulder —30— on the rod, as shown in Fig. 1, the spring serving not only to 30 retract the rod —26—, but also to return the rock arm —23— and pawl —22— to their starting positions to engage the next adjacent tooth of the ratchet wheel —21—.

The binding post as —31— of the switch 35 may be connected by wires —32— to any available source of current supply capable of operating the motor.

In order that the tool holder as —33— carrying the grinding tool or lap as —a— 40 may be driven at the desired speed, it is secured by a set screw —34— to the upper end of a shaft extension —5'— co-axial with but separate from the shaft —5— and connected to said shaft by suitable gearing 45 presently described.

The upper end of the shaft —5— is tapered and tightly fitted in a corresponding socket of a sleeve —35—, telescoping within another sleeve —36— on the lower end 50 of the shaft section —5'— so that the two shafts may be rotated relatively to each other at the same or different speeds, the sleeves and shaft sections —5— and —5'— being held exactly co-axial and against relative endwise movement by anti-friction end thrust bearings —37—.

The lower end of the sleeve —35— is provided with a pinion —38— meshing with a relatively larger gear —39— on an upright 60 countershaft —40— which is journaled in suitable bearings in the bottom and top of the case —6— and is provided with a pinion —41— meshing with a relatively larger gear —42— on the lower end of the sleeve 65 —36—, thus completing the gear train for

transmitting rotary motion from the shaft —5— to the co-axial shaft section —5'— carrying the tool holder —33— and causing the tool holder to be rotated at a lower rate of speed than that of the motor, the gear 70 —14— on the shaft —5— being also relatively larger than that on the motor shaft extension —15—.

The shaft —5'— is not only journaled at its lower end upon the sleeve —35—, but is 75 also journaled intermediate its ends in a bearing —43— on the cap —11— close to the tool holder —33— which serves to maintain an exact co-axial relation between the tool holder and its driving shaft —5—, and 80 also reduces to a minimum the liability of vibration of the tool holder which might affect the accuracy of the grinding of the surface of the lens.

The lens as —b— is secured in the usual 85 manner by paste or other adhesive to one of two relatively movable lens-holding sections —44— of any well-known construction, the other section being rigidly secured to a centering pin or spindle —45— on one of 90 the sections as —46— of a flexible shaft —47— to move endwise therein, and together with the lens holder —44— is spring-pressed toward the tool —a— by a coil spring —48— acting upon the inner end of 95 the centering pin or spindle —45— which is keyed to the shaft section —46— by a screw —49— to rotate therewith, the screw —49— being passed through a slot —50— in the adjacent side of the shaft section 100 —46— to allow relative endwise movement of the parts —45— and —46—, thus permitting the lens holder to be lifted from the grinding or polishing tool —a— against the action of the spring —48— to remove 105 the section to which the lens is secured when desired for inspection or other purposes.

The upper end of the shaft section —46— is connected by a universal joint —51— to an upwardly extending shaft section —52— 110 which is feathered or splined to an adjacent shaft section —53— to rotate therewith and allow the sections to be adjusted lengthwise of each other, the section —53— being connected by a universal joint —54— to a 115 vertical shaft section —55—.

This section —55— is journaled in the front end of a horizontal bracket —56— co-axial with the axis of movement of the tool holder —33— and is connected by gears 120 —57— to a horizontal shaft —58— also journaled in bearings in the bracket —56— which is secured to an upright standard —59— rising from the rear side of the bed or table —2—.

The rear end of the upper horizontal shaft —58— is connected by beveled gears —60— to an upright shaft —61— which is journaled at its lower and upper ends in bearings 125 —62— on the standard —59— and is 130

connected at its lower end by beveled gears —63— to a forwardly extending horizontal shaft —64—.

This shaft —64— is journaled in suitable bearings —65— on a rearward extension —66— of the case —6— and is connected by beveled gears —67— to the sleeve —36— on the lower end of the shaft section —5— so that the tool holder and work holder are driven from the same source of power and, therefore, in synchronism, the gear connections between the shaft —5— and flexible shaft —47— being so arranged and proportioned as to drive the work holder in the same direction and at the same rate of speed as the tool holder.

Planetary motion.

In grinding or polishing cylindrical, spherical or toric surfaces of different degrees of curvature by means of a rotary tool, it is desirable to progressively shift the position of the lens relatively to the tool so as to avoid cutting circular lines or channels in the lens by regular recurrent rubbing contact between the same points of the lens and tool, and for this purpose, I have provided means for imparting a planetary motion to the lens holder relatively to the tool, but in an opposite direction, and at a different rate of speed, in this instance, one-fourth the speed of movement of the tool and lens holder about their respective axes so that when these parts are properly set at the beginning of the operation for grinding a toric lens, the corresponding axes of the different curves of the tool and lens are always registered with each other on each quarter turn of the tool or lens holder.

These results are accomplished by deflecting and holding a portion of the flexible shaft —47— to one side of the axis of the tool holder and then rotating the deflected portion about said axis, the degree of deflection depending upon the degree of curvature of the grinding or polishing surface to bring the axis of the lens-supporting spindle —45— approximately radial to such surface, and for this purpose, the shaft section —46— carrying the lens-supporting spindle —45— is journaled in a sleeve —68— passing through a slotted plate —69— and held against rotation by radial pivotal pins —70— in opposite sides of the plate and entering holes in opposite sides of the sleeve to allow the latter to adjust itself to different angles as the plate is adjusted in setting the flexible shaft section —46— at the desired angle, after which the sleeve is held in its adjusted position by a set screw —71—, Figs. 3 and 4.

The plate —69— and portion of the flexible shaft passing therethrough are arranged within a relatively large horizontal gear —72— which is journaled in a suitable

frame —74—, the latter being supported upon a bracket —75— projecting forwardly from the upright standard —59—, as shown in Figs. 1, 2 and 3, the plate —69— being adjustable diametrically of the gear along 70 ways —76— forming a part of said gear and rotating therewith in the direction indicated by arrow —x—, Fig. 3.

The rear side of the gear —72— meshes with a pinion —77— on the front end of a 75 horizontally disposed shaft —78— which is journaled in suitable bearings —79— and —80— on the frame —74— and bracket —75—, respectively.

The rear end of the horizontal shaft 80 —78— is connected to the upright shaft —61— by beveled gears —81—, thus synchronizing the rotation of the gear —72— and planetary movement of the lens holder with the rotary movement of the tool holder, 85 the ratio of the gears —72— and —81— being four to one so that the lens holder will travel one-fourth of its cycle during each revolution of the tool holder, thereby causing like axes of the tool holder and lens to 90 register each quarter revolution of those parts about their respective axes which is important, particularly in grinding toric lenses.

In order to further reduce the liability of 95 cutting objectionable grooves or channels in the lenses during the grinding or polishing operation, I have provided simple means for shifting the lens holder back and forth relatively to its orbit consisting, in this instance, of a pair of eccentrics —82— mounted upon a horizontal shaft —83— which is journaled in suitable bearings on the upright standard —59— and is driven from the upright shaft —61— by angle gears 100 —84—, said eccentrics being connected by pitmen —85— to opposite sides of the frame —74—, as shown more clearly in Fig. 3, said frame being movable along and upon ways —86— on the front end of the 110 bracket —75—.

When the slide —69— is adjusted to the desired position, it is held in such position by means of a set screw —71'—, thereby causing the lens to travel in a circular orbit 115 around and upon the face of the tool —a—, it being understood that the gear —72— is co-axial with the axis of the tool holder —33— and mandrel —55— and that the degree of adjustment of the slide —69— depends upon the curvature of the surface of 120 the tool.

It is also evident that in grinding convex surfaces, the slide and lens holder will be at the same side of the axis of the tool 125 holder, while in grinding concave lenses, the slide and lens holder will be at opposite sides of said axis without changing the speed or direction of planetary motion of the lens.

What I claim is:

1. In a lens grinding and polishing machine, a rotary work holder adjustable to different angles relatively to the axis of the 5 tool holder, means for locking the work holder in its adjusted position, a rotary tool holder, and mechanism for rotating the work holder and tool holder in the same direction and at the same rate of speed.
- 10 2. In a lens grinding and polishing machine, a rotary tool holder and a rotary lens holder coöperating therewith, means for driving the tool holder and lens holder in the same direction and at the same rate of 15 speed, additional means for moving the lens holder in an orbit about the axis of, but in an opposite direction to and at a different rate of speed than the tool holder, and co-operative means for reciprocating the lens holder relatively to its orbit and during its 20 planetary motion.
3. In a machine for grinding and polishing lenses, co-axial rotary shaft sections, driving means for one of said sections, a 25 tool holder carried by one of the sections to rotate therewith, means for driving the other section, means driven by the last-named section for driving the tool-carrying section at a different rate of speed, a lens- 30 holding section coöperating with the tool holder, means for moving the lens holder in an orbit about the axis of the tool holder, but in an opposite direction and at a different rate of speed, and additional means for 35 rotating the lens holder in the same direction and at the same rate of speed as the tool holder.
4. In a lens grinding and polishing machine, a rotary tool holder and actuating 40 means therefor, in combination with a mandrel co-axial with the tool holder, a flexible shaft connected to the mandrel, a lens holder on the flexible shaft, means for rotating the mandrel in the same direction and at the 45 same rate of speed as the tool holder, and additional means for deflecting a portion of the flexible shaft to one side of said axis and rotating it in an orbit about the same, but at a less speed than that of the mandrel and 50 tool holder.
5. In a lens grinding and polishing machine, in combination with a rotary tool holder and actuating means therefor, a revolute member co-axial with the tool holder,
- driving means for said member, a rotary 55 shaft passing through said member and adjustable toward and from its axis, means for holding the portion of the shaft passing through the member in its adjusted position, a lens holder carried by the shaft to co-operate with the tool holder, means for rotating the shaft, and additional means for reciprocating said revolute member radially.
6. In a machine for grinding and polishing lenses, the combination of the grinding element, a rotary shaft carrying a work holder, means for adjusting the work holder shaft to different angles relatively to the grinding element, and means for carrying 70 said shaft at the adjusted angle in a planetary motion about the produced axis of the grinding element.
7. In a machine of the character described, the combination of a rotary tool 75 holder and actuating means therefor, a flexible shaft having a work holder thereon, and means for deflecting a portion of said shaft to one side of a direct line between its ends and for rotating such deflected portion in an 80 orbit about the produced axis of the tool holder.
8. In a machine of the character described, the combination of a tool holder and a coöperative work holder, shaft sections 85 connected by a universal joint, the work holder being secured to one of said shaft sections, means for deflecting the shaft sections at the joint and for holding them at an angle to each other, and means for moving the joint in an orbit about the produced 90 axis of the tool holder.
9. In a machine of the character described, the combination of a rotary tool holder and actuating means therefor, a work 95 holder and a rotary driving element therefor adjustable to different angles relatively to the axis of the tool holder, and means for holding said element in its adjusted position and for moving it in an orbit about said 100 axis.

In witness whereof I have hereunto set my hand this 24th day of May, 1915.

ERNEST STEAD.
